FIG. 5

UNITED STATES PATENT OFFICE

SHERMAN H. HALVORSEN, OF SAN DIEGO, CALIFORNIA

ANATOMICAL ARTICULATOR

Application filed September 25, 1929. Serial No. 395,002.

My invention relates to anatomical articulators, and the objects of my invention are: First, to provide a device of this class which readily receives a set of false teeth and grinds them until more perfect articulation is obtained; second, to provide a device of this class in which upper and lower sets of false teeth of any style or size may be readily and quickly inserted, positioned relative to each other, or removed; third, to provide a device of this class which, after the sets of teeth have been positioned and arranged in the relation they normally assume when the mouth is closed, and secured to the said device, may be manipulated so that the sets of teeth shift relative to each other and duplicate the movements they undergo when in the mouth; fourth, to provide a device of this class which, after once being adjusted for the particular set of teeth, permit removal and replacement of said set of teeth with very little adjustment; fifth, to provide a device of this class which eliminates the need of cement, plaster of Paris, or the like, for holding sets of false teeth in certain relation to the articulator, thereby greatly facilitating the operation of grinding a pair of false teeth sets into proper articulation; sixth, to provide a novelly constructed clamp for securing false teeth; and seventh, to provide on a whole a novelly constructed anatomical articulator, which is simple of construction proportional to its functions, easily adjusted and manipulated, compact, sturdy of construction, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a front elevational view of my articulator shown in its open position, with an upper and a lower set of false teeth shown in relation thereto and fragmentarily; Fig. 2

is a side elevational view of my articulator shown in its closed position, with sets of false teeth shown in relation thereto; Fig. 3 is a top or plan view of my articulator shown in its open position, and with sets of false teeth secured thereto and shown fragmentarily; Fig. 4 is a sectional view of my articulator taken through 4—4 of Fig. 1, with parts and portions shown in elevation to facilitate the illustration; Fig. 5 is a fragmentary sectional view through 5—5 of Fig. 3, with parts and portions shown in elevation to facilitate the illustration; Fig. 6 is an enlarged fragmentary sectional view through 6—6 of Fig. 5; Fig. 7 is a slightly enlarged fragmentary elevational view of the inside clamping members and their supports, with adjacent portions shown fragmentarily and parts and portions broken away and in section to facilitate the illustration; Fig. 8 is a fragmentary sectional view through 8—8 of Fig. 7; and Fig. 9 is a fragmentary sectional view through 9—9 of Fig. 3.

Similar characters of reference refer to similar parts and portions throughout the several views of the drawings.

Base member 1, guide pins 2, sliding table 3, table shifting screw 4, leg members 5, cushions 6, retainer block 7, inner clamp bars 8, outer clamp bars 9, screw members 10, journal pins 11, oscillating arms 12, springs 13, pins 14, cross rod 15, binding post 16, binding post clamp screw 17, rod 18, socket means 19, clamp screw 20, secured support plate 21, guide pins 22, sliding support plate 23, shifting screw 24, clamp arms 25, rear clamp lever 26, pin 27, wedge member 28, arm members 29, set screws 30, arm members 31, and set screws 32, constitute the principal parts and portions of my anatomical articulator.

A base member 1 is provided which is relatively broad and flat. Pins 2 extend horizontally from the forward end of the base member 1 and fit in sockets 3a of a sliding table 3. The upper and lower surfaces of the sliding table 3 are substantially flush with the corresponding surfaces of the base member 1.

Centered between the pins 2, extending through the sliding table 3 and into the base member 1, is a table shifting screw 4, which

has a knurled head 4a at its forward end so that the screw may be turned by hand and shift the table inwardly and outwardly relative to the base member 1.

The sliding table 3 and base member 1 are each provided with a pair of downwardly extending leg members 5, which are capped with cushions 6 made of rubber or the like.

Positioned in centered relation over the shifting screw 4 and directly forward over the table 3, is a bracket member 1a, which forms a part of the base member 1. Positioned between the overhanging portion of the bracket 1a and the upper side of the table 3, is a retainer block 7. Said retainer block is held relative to the bracket 1a by means of a screw 7a, which extends through a slot 1b positioned transversely relative to the bracket 1a, as shown best in Figs. 3, 4, and 7.

The retainer block 7 is substantially triangular, with its apex pointing forward. The two forward sides joining the apex of the retainer block are provided with horizontally extending ear portions 7b, which are spaced apart from the upper surface of the table 3. Each of the ear portions 7b receives thereunder an inner clamp bar 8. Each inner clamp bar 8 is held in limited shiftable relation to the ear portions 7b by means of a projection 7c, which depends from the corresponding ear portion and extends into a longitudinally extending channel 8a provided in the upper side of the corresponding clamp bar 8. This structure is shown best in Fig. 7.

The ends 8b and 8c of each inner clamp bar 8 are upturned and enlarged at the sides of their extremities facing away from the retainer block. Suitable padding 8d is provided on these enlarged portions 8b and 8c. The retainer block is capable of limited side-wise movement by reason of the slot 1b. The inner clamp bars may be shifted forwardly and rearwardly as well as rotated slightly by reason of the projections 7c and channels 8a, as indicated by the arrows in Fig. 3.

Positioned outwardly and forwardly of each inner clamp bar 8 is an outer clamp bar 9, which is secured in rotatable relation to the table 3 by a screw member 10 extending through said outer clamp bar near the forward end thereof, as shown best in Fig. 3. The ends 9a of each outer clamp bar 9 are upturned, then bent inwardly toward the inner clamp bars 8. The extended ends of these upturned portions 9a receive pad members 9b.

At the rear outer corners of the base member 1, there are provided two upwardly extending post members 1c. At the upper end of each post on the inner side thereof, there is rotatably secured thereto, by means of a journal pin 11, an oscillating arm 12. Extending forwardly from the inner side of each oscillating arm 12 is a handle portion 12a, which is bent intermediate its ends so

that the extended portion overlaps the forward side of the corresponding post 1c.

A lug 1d extends inwardly from the forward side of each post 1c so as to engage the forward side of the corresponding oscillating arm 12 when said oscillating arm is moved into its forward position.

A spring 13 is supported adjacent each post 1c at the inner side thereof by means of a pin 14 secured to said post. The one end of each spring 13 engages the rear side of the corresponding oscillating arm 12 and yieldably holds it against a lug 1d. The other end of each spring is anchored in the base member 1.

Rearward movement of the handles 12a causes the oscillating arms 12 to rotate against the action of the springs 13 until stopped by the overhanging portions of the handles 12a engaging the lugs 1d, as shown by the dotted lines in Fig. 5.

The depending portion of each oscillating arm 12 is provided with a socket 12b therein, which opens inwardly. Supported by its ends, between the two sockets 12b is a cross rod 15. Secured to the cross rod 15, in centered relation thereto is a binding post 16, which extends at right angles to the cross rod. Except for its secured portion, the binding post 16 is split, as indicated by 16a. An opening 16b is provided near the extended end of the binding post. Said opening 16b is centered relative to the bifurcated portions of the binding post and is adapted to receive a rod 18 which extends at right angles to both the binding post and the cross rod 15. A clamp screw 17 is adapted to draw the ends of the bifurcated portions of the binding post together so as to clamp the rod 18. The forwardly or upwardly extending end of the rod 18, depending upon its position, is provided with a ball portion 18a which fits inside of a socket 19, the one half of which is integral with a support plate 21. The other half 19a of said socket is adapted to be drawn toward the first mentioned half of the socket by means of a clamp screw 20 so as to clamp the ball portion 18a in any desired position relative to the socket member 19.

The plate 21 is relatively flat, and has projecting from its rear edge, that is the edge facing the binding post 16, a pair of spaced apart guide pins 22 which fit in sockets formed in a sliding support plate 23, which is similar in shape to the plate 22. The sliding plate 23 is adapted to be shifted relative to the plate 21 by means of a shifting screw 24, similar to the shifting screw 4, which extends through the stationary or supported plate 21 and into the sliding plate 23.

A suitable knurled head 24a is provided on the forward end of the shifting screw 24 so that said screw may be operated by hand. At the forward portion of the plate 21 at the opposite side thereof from the socket members 19, are a pair of clamp arms 25, the ex-

tended ends of which are turned rearwardly and are provided with pads 25a. The bent or horizontally extending portions of the arms 25 extend towards the common center so that the extended end surfaces of said portions may readily engage the curved outer surface of the upper set of false teeth.

Formed integral with the sliding plate 23, on the same side as the arms 25, is a block portion 23a. A rear clamp lever 26 is pivoted intermediate its end on the block portion 23a by means of a pin 27. The extended ends of the clamp lever 26 are upturned and provided with pads 26a, the forward surfaces of which are adapted to engage the rear edge of an upper set of false teeth. The block portion 23a is provided with an opening 23b, therethrough which extends longitudinally with the plate members 21 and 23.

Slidably mounted in this opening by its one end is a wedge member 28, the one surface of which rides upon the surface of the plate 23, and the other surface of which is inclined relative to said plate 23. The sloping or wedge surface 28a of the wedge member 28 is positioned between the cross arms 25 and clamp lever 26 so as to engage the roof of the upper set of false teeth. The wedge member 28 is slidable relative to the supporting plate 23 so that the roof of the upper set of false teeth may be properly spaced away from plates 21 and 23 by shifting the wedge member 28 forwardly or rearwardly.

Pivoted to the plate 21, on the side thereof having the arms 25, which is the lower side of said plate, are a pair of arm members 29. These arm members are pivotally secured at their one ends adjacent the rear edge of said lower side and extend forwardly so as to register with openings 21a provided in the plate 21. A set screw 30 is screwably mounted in the extended end of each arm member 29 in transverse relation to the plate 21. The one end portion of each screw 30 is provided with a suitable head 30a which is adapted to engage the gum fitting channel of the upper set of teeth. Adjustment of the set screws 30 facilitates in the proper spacing of the upper set of false teeth relative to the plate 21.

In the U-shaped space formed between the pairs of inner clamp bars 8 and the corresponding pairs of outer clamp bars 9, the sliding table 3 is provided with recess portions 3a, one pair located near the rear end of said sliding table approximately between the corresponding rear ends of the clamp bars 8 and 9, and the other pair of recesses 3b located near the forward side of the sliding table approximately between the forward ends of the corresponding clamp bars 8 and 9, as shown best in Fig. 3.

Within each recess portion 3b, there is pivotally mounted at its one end, by means of a pin 31a, an arm member 31, the upper

surface of which is flush with the upper surface of the sliding table 3, as shown best in Fig. 9.

An arcuate slot 3c, having the center of its curvature at the axis of the pin 31a securing the arm member 31, intersects the recess portion 3b. A set screw 32 extends through the slot 3c and is screwably mounted in the arm 31. The lower end 32a of each set screw 32 is provided with a knurled head 32b which may be readily grasped for lowering and raising said set screw relative to the upper surface of the sliding table 3.

The operation of my anatomical articulator is as follows:

Previous to grinding the teeth, wax or the like has been placed thereon, they have been inserted in the patient's mouth, and the patient has bitten down making an impression in the wax. The lower set of false teeth is placed between the clamp bars 8 and 9 with the molar teeth at the rear, as shown best in Figs. 1, 2, and 3. The inner clamp bars 8d are then shifted until the pads 8d thereof engage the inside walls of the lower set of teeth. Then the screw 4 is turned, shifting the table and clamp bars 9 until the padded portion 9b of said bars engages the outside walls of said lower set of teeth, as shown best in Fig. 3. The upper set of teeth is then positioned between the clamp arms 25 and the clamp lever 26 and the plates 21 and 23, by means of the arm 18, and the ball and socket joint connecting said arm with the plate 21 is shifted until the upper and lower sets of teeth register with the wax impressions previously made. The clamp screws 17 and 20 are tightened; the wax is then removed and suitable grinding compound is spread over the teeth.

First one and then the other of the oscillating arms 12 is moved, (the ends of the rods 15 fitting with sufficient looseness in the socket 12b to permit this movement) causing the upper set of teeth to shift relative to the lower set of teeth with a relative movement similar to the movement obtained when the teeth are in the patient's mouth. Thus, high spots may be readily ground down, and a more perfect bite may be obtained.

Usually the set screws 30 and 32 need not be used. When it is desirable to use them, the set screws 32 are turned until they engage the deep portion of the channel formed in the lower set of false teeth A, which is adapted to fit over the gums. When the lower set of false teeth has been properly positioned, the set screws 30 may be adjusted so as to move the upper set of false teeth into proper relation thereto.

Though I have shown and described a particular construction, combination and arrangement of parts and portions, I do not wish to be limited to this particular construction, combination and arrangement, but de-

sire to include in the scope of my invention the construction, combination and arrangement substantially as set forth in the appended claims.

6. Having thus described my invention, what I claim as new and desire to secure by Letters Patent is:

1. In an articulator for false teeth, a first clamp mechanism comprising a set of shiftable clamp bars arranged to engage portions of the inside margins of a lower set of false teeth, a second set of shiftable clamping bars movable relative to said first set of clamping bars arranged to engage portions of the outside margins of said lower set of false teeth, the clamp bars of both sets being pivotable about axes intermediate their respective ends and a shifting screw for causing said sets of clamping bars to engage and hold said lower set of false teeth, a second clamp mechanism comprising a clamp member arranged to engage the rear margins of an upper set of false teeth, said clamp member being pivotable about an axis intermediate its ends and other clamp members arranged to engage the forward margins of said upper set, and a shifting screw for causing said clamp members to engage and hold the upper set of false teeth, and means for setting said second clamp mechanism relative to said first clamp mechanism so that the teeth of said upper and lower sets mesh.
2. In an articulator for false teeth, a clamping mechanism comprising a base portion and a table portion, a set of clamping bars shiftably connected with said base portion and arranged to engage the inside margins of a lower set of false teeth at several points, a second set of shiftable clamp bars mounted on said table portion arranged to engage the outer margins of said lower set of false teeth at several points, and means for shifting said table portion relative to said base portion so as to cause said clamping bars to hold said lower set of false teeth.
3. In an articulator for false teeth, a first clamping mechanism comprising a base portion and a table portion, a set of clamping bars shiftably connected with said base portion and arranged to engage the inside margins of a lower set of false teeth at several points, a second set of shiftable clamp bars mounted on said table portion arranged to engage the outer margins of said lower set of false teeth at several points, means for shifting said table portion relative to said base portion so as to cause said clamping bars to hold said lower set of false teeth, a second clamping mechanism arranged to releasably secure an upper set of false teeth, spacing screws arranged to shift laterally with respect to their axes associated with the sliding table of said first clamping mechanism arranged to space said lower set of false teeth therefrom, spacing means arranged to shift laterally with respect to their axes associated with said second clamping mechanism for spacing said upper set of false teeth therefrom, and means for setting said second clamp mechanism relative to said first clamping mechanism so that the teeth of said upper and lower sets mesh.
4. In an articulator for false teeth, a first

clamping mechanism comprising a base portion and a table portion, a set of clamping bars shiftably connected with said base portion and arranged to engage the inside margins of a lower set of false teeth at several points, a second set of shiftable clamp bars mounted on said table portion arranged to engage the outer margins of said lower set of false teeth at several points, means for shifting said table portion relative to said base portion so as to cause said clamping bars to hold said lower set of false teeth, a second clamping mechanism comprising a pair of plate members arranged to move to and from each other, a clamping lever rotatably supported intermediate its ends on one of said plate members arranged to engage the rear side of an upper set of false teeth, clamping arms on the other of said plate members arranged to engage the forward side of said upper set of false teeth and a screw means for shifting said plate members relative to each other, and means for setting said second clamp mechanism relative to said first clamp mechanism so that the teeth of said upper and lower sets mesh.

5. In an articulator for false teeth, a first clamping mechanism comprising a base portion and a table portion, a set of clamping bars shiftably connected with said base portion and arranged to engage the inside margins of a lower set of false teeth at several points, a second set of shiftable clamp bars mounted on said table portion arranged to engage the outer margins of said lower set of false teeth at several points, means for shifting said table portion relative to said base portion so as to cause said clamping bars to hold said lower set of false teeth, a second clamping mechanism arranged to releasably secure an upper set of false teeth, spacing screws arranged to shift laterally with respect to their axes associated with the sliding table of said first clamping mechanism arranged to space said lower set of false teeth therefrom, spacing means arranged to shift laterally with respect to their axes associated with said second clamping mechanism for spacing said upper set of false teeth therefrom, and means for setting said second clamp mechanism relative to said first clamping mechanism so that the teeth of said upper and lower sets mesh.

6. In an articulator for false teeth, a first clamping mechanism comprising a base portion and a table portion, a set of clamping bars shiftably connected with said base portion and arranged to engage the inside margins of a lower set of false teeth at several points, a second set of shiftable clamp bars mounted on said table portion arranged to engage the outer margins of said lower set of false teeth at several points, means for shifting said table portion relative to said base portion so as to cause said clamping bars

to hold said lower set of false teeth, a second clamping mechanism comprising a pair of plate members arranged to move to and from each other, a clamping lever rotatably supported intermediate its ends on one of said plate members arranged to engage the rear side of an upper set of false teeth, clamping arms on the other of said plate members arranged to engage the forward side of said 5 upper set of false teeth and a screw means for shifting said plate members relative to each other, spacing screws arranged to shift laterally with respect to their axes associated with the sliding table of said first clamping 10 mechanism arranged to space said lower set of false teeth therefrom, spacing means arranged to shift laterally with respect to their axes associated with said second clamping mechanism for spacing said upper set of false 15 teeth therefrom, and means for setting said second clamp mechanism relative to said first clamping mechanism so that the teeth of said upper and lower sets mesh.

7. In an articulator for false teeth, a first 20 clamping unit comprising a support, a laterally shiftable connecting member and a pair of clamping levers pivotally connected with said connecting member, and a second clamping unit comprising a support means, and 25 a pair of spaced apart clamping bars connected therewith, said clamping bars being pivotally mounted intermediate their ends, and means for shifting said clamping units toward and from each other whereby a set 30 of false teeth may be clamped by said clamping levers and clamping bars.

8. In an articulator for false teeth, a base, a table, means for shifting said table toward and from said base, a plurality of clamping 40 elements connected with said base, and a plurality of clamping units connected with said table, each of said clamping elements and clamping units being revolvably mounted intermediate their respective ends each of said 45 clamping elements and clamping units upon contacting with the walls of a set of teeth at more than one place being arranged to lock against further rotary movement.

9. In an articulator for false teeth, a 50 clamping structure for an upper set of false teeth including a fixed support, a shiftable support, means for shifting said latter support towards and from said fixed support, fixed clamping units carried by said shiftable support, a clamping bar carried by said fixed support, said clamping bar being pivotable intermediate its ends, a spacer in the form of a 55 slidable wedge carried by said fixed support, arm members rotatably supported by said shiftable support and spacing screws carried at the extended portions of said arm members.

10. In an articulator for false teeth, a 60 clamping structure for a lower set of false teeth including a base, a table, means for 65

shifting said table toward and from said base, a plurality of clamping elements connected with said base, and a plurality of clamping units connected with said table, each of said clamping elements and clamping units being 70 revolvably mounted intermediate their respective ends, each of said clamping elements and clamping units upon contacting with the walls of a set of teeth at more than one place being arranged to lock against further rotary movement, a clamping structure for an upper set of false teeth including a fixed support, a shiftable support, means for shifting said latter support toward and from said fixed support, fixed clamping units carried by said 75 shiftable support, a clamping bar carried by said fixed support, said clamping bar being pivotable intermediate its ends, a spacer in the form of a slidable wedge carried by said fixed support, arm members rotatably supported by said shiftable support, spacing screws carried at the extended portions of said arm members and frame means for connecting said clamping structures whereby said set of teeth occupy an articulated relation.

11. In an articulator for false teeth, a base, a table, means for shifting said table toward and from said base, a plurality of clamping elements connected with said base, and a plurality of clamping units connected with said table, each of said clamping elements and clamping units being revolvably mounted intermediate their respective ends, each of said clamping elements and clamping units upon 80 contacting with the walls of a set of teeth at more than one place being arranged to lock against further rotary movement, arm members rotatably supported by said table, and spacing screws arranged at the extended portions of said arms, whereby said spacing screws are shiftable so as to engage the floor of the gum enveloping portion of a set of false teeth supported by said clamping elements and clamping means.

12. In an articulator for false teeth, a clamping structure arranged to support a set of false teeth, a pair of uprights extending from said clamping structure, an arcuately shiftable arm depending from the upper portion of each upright, a cross bar loosely connected with the depending portions of said arms and extending therebetween, the points of connection between said cross bar and said arms occupying, with respect to a set of teeth supported by said clamping structure, positions corresponding approximately to the fulcrum points of the mandible of a human being, a post joined to said cross bar, a rod adjustably associated with said cross bar and arranged to extend over said clamping structure, and a clamping means depending from said rod arranged to support a second set of false teeth which are complementary to said first set of false teeth, said 125

arms being independently and simultaneously shiftable with respect to said uprights whereby said second set of false teeth may be shifted with respect to said first set of false teeth in a manner simulating their relative movements in a human's mouth.

In testimony whereof, I have hereunto set my hand at San Diego, California, this 11th day of September, 1929.

10 SHERMAN H. HALVORSEN.
